203,636

STYLING STAND FOR A WIG-BLOCK OR SIMILAR ARTICLE

Philip Goldblatt, 671 W. 193rd St., New York, N.Y.

Filed Mar. 11, 1964, Ser. No. 78,956

Term of patent 3½ years

(Cl. D80—9)

FIG. 1 is a perspective view of a styling stand for a wig-block or similar article embodying my new design;
FIG. 2 is a front elevational view thereof;

FIG. 3 is a top view thereof; and

FIG. 4 is a bottom view thereof

I claim:

The ornamental design for a styling stand for a wig-block or similar article, as shown.
